CONTAINER OF TRANSPARENT CELLULOSE FILM

Louis E. Membrino, Upper Darby, Pa.

Application December 16, 1935, Serial No. 54,563

1 Claim. (Cl. 229—3.5)

The inherent character of transparent cellulose in sheet form, as usually employed to make containers, is light in weight and delicate in texture. While it is tough and capable of resisting strain, it is without perceptible grain and tears easily in any direction when the tear or cut has once been started. Considerable difficulty is encountered in the manufacture of pliated and creased containers because often the film texture is injured and its resistance is weakened in the process of making the folds and creases. The same difficulty, in a varied degree, is experienced with thin sheets of opaque or semi-transparent papers.

It is an object of this invention to produce a container of transparent cellulose film or of other thin paper that has no sharp folds or creases.

A more particular object of my invention is to provide a container of transparent cellulose film, or of similar thin paper, that will stand erect and open when empty.

My invention consists of a combination of a heavy paper or cardboard cup having a flange or wall of about one quarter of an inch or more in height and a tube of transparent cellulose film or of similar thin paper. The cup is inserted into one end of the tube so that the edge of the tube is flush with the bottom of the cup. The tube is fastened to the cup with adequate adhesive, thus forming a cylindrical receptacle.

With the above and related objects in view, my invention consists in the details of construction and combination of parts, that will be hereinafter fully described and the description will be more readily understood when it is read in conjunction with the accompanying drawing in which:

Fig. 1 is a perspective view of the complete container embodying my invention.

Fig. 2 is a perspective view of the heavy paper or cardboard disc which forms the base of my improved container.

Fig. 3 is a perspective view of the cylindrical transparent cellulose film or tube.

Fig. 4 is a fragmentary sectional view of my complete container.

Referring in greater detail to the drawing, a cylindrical transparent cellulose film or sheet of "cellophane", generally designated as *a*, is formed into a hollow tube by gluing two overlapping parallel edges of the film or sheet together. However, a seamless tube may be used.

A container base, cup, or drum, comprises a heavy paper or cardboard cup having a disc-like member *b* and a peripheral flange *c* turned at right-angles to the disc-like member *b*. The base or cup is inserted into one end of the tube so that the edge of the tube is flush with the disc-like member *b* of the cup. The flange of the base interfits with the lower interior surface of the "cellophane" tube, and the base and tube are securely fastened together by means of suitable adhesive. This container bottom is non-sifting, air-tight and non-transparent. Thus, the fragments and sediment of the container contents are shielded from view. It should be observed that the entire container will stand erect and open when empty.

I am aware that, prior to my invention, cylindrical packages have been made of transparent cellulose film and of other thin paper sheets and therefore I do not claim a cylindrical container broadly, but

I claim:

The combination of a flimsy hollow cylindrical-like container comprising a cylindrical tube of transparent cellulose film, a disc-like member having a peripheral flange interfitting within one end of said cylindrical tube so that the lowermost edge of the film is flush with the bottom of said disc-like member whereby the container will stand erect, said flange having its outer surface in engagement with the lower interior surface of the film, said disc-like member being of substantially greater weight than the cylindrical container film so that the device will stand erect, and said interfitting and flanged disc member making the bottom of said container non-sifting, air-tight, and non-transparent.

LOUIS E. MEMBRINO.
